UNITED STATES PATENT OFFICE.

JOHN A. MORRISON, OF MANSFIELD, OHIO.

HOISTING MECHANISM.

Application filed May 31, 1923. Serial No. 642,463.

To all whom it may concern:

Be it known that I, JOHN A. MORRISON, a citizen of the United States, residing at Mansfield, in the county of Richland and State of Ohio, have invented certain new and useful Improvements in Hoisting Mechanism, of which the following is a specification.

This invention relates to hoisting mechanism and the objects of the improvement are to provide mechanism of this class in which the load is counterbalanced, thus requiring very little power to raise a considerable weight.

The above and other objects may be attained by providing a frame in which a lifting bar is vertically slideable and arranged to support the load, a vertically slideable block being mounted adjacent to the lifting bar and carrying a pinion meshing with a rack upon the lifting bar, a flexible member being connected to the lifting bar and passed upward over a pulley and downward to a point of connection with the slideable block, means being provided for normally preventing rotation of the pinion and for rotating the same in either direction to raise or lower the lifting bar.

An embodiment of the invention thus set forth in general terms is illustrated in the accompanying drawing, in which—

Figure 1 is a side elevation of a hoisting mechanism embodying the invention;

Fig. 2, an edge elevation of the same;

Fig. 3, a side elevation of the slideable block; and

Fig. 4, a plan view of the same.

Similar numerals refer to similar parts throughout the drawing.

The mechanism is mounted in a frame comprising the base 1 and the spaced, parallel upright guides 2 and 3, preferably connected at their upper ends as at 4 for the purpose of strengthening the same.

The lifting bar 5 is slidably mounted in the guide-way 2 and provided with a head 6 at its upper end to receive the load, rack teeth 7 being formed upon the inner face of the bar.

A channel shaped block 8 is slidably mounted in the guide-way 3 and the shaft 9 is journaled transversely therethrough, a pinion 10 being fixed upon the shaft with in the channel portion of the block and

meshing with the rack teeth 7 of the lifting bar.

A worm gear 11 is fixed upon each outer end of the shaft 9. A spaced pair of ears 12 extends outward from each side of the block 8 forming bearings for the worm shafts 13, the worms 14 thereon meshing with the worm wheels 11, ball bearings 15 preferably being provided upon said worms.

The outer end of each worm shaft is provided with a flat sided shank 16 to receive the socket of a suitable tool for rotating the same, and pinions 17 are fixed upon the worm shafts and mesh with an idler 18 journaled as at 19 upon the frame.

A sprocket chain or other flexible member 19^a is connected to each side of the block 8 at the upper end thereof, preferably through the boss 20 and passes upward over a sprocket wheel or pulley 21 and downward to an ear 22 fixed upon the outer side of the lifting bar 5 and extended through the vertical slot 23 in the frame.

Thus as the load is placed upon the upper end of the lifting bar, the same will be equally distributed between the lifting bar and the block 8 as a portion of the load is transmitted through the chains 19^a over the pulley 21 to the block 8.

The worms 14 meshing with the worm wheels 11 normally prevent rotation of the shaft 9, thus holding the parts against movement by the placing of the load upon the lifting bar. By rotating either of the shafts 13 with a suitable tool as above described, the motion will be transmitted through the gears 17 and 18 to the opposite worm shaft, rotating both of the worm wheels and through the same the shaft 9 and pinion 10 to raise or lower the lifting bar, moving the block 8 in the opposite direction, maintaining the flexible members 19^a taut, while under load.

As the load is thus balanced between the lifting bar and the slideable block 8, it will be seen that the load itself assists greatly in raising the lifting bar, greatly reducing the amount of power necessary to rotate the worms 14 to raise the load.

I claim:—

1. A hoisting mechanism including a vertically movable rack bar, a vertically movable block, a pinion carried by the block meshing with the rack bar, a pulley, a flexi-

ble member extended upward over the pulley and connected at opposite ends to the rack bar and block, means for normally preventing rotation of the pinion, and means for 5 rotating the pinion to raise or lower the rack bar.

2. A hoisting mechanism including a vertically movable rack bar, a vertically movable block, a pinion carried by the block, 10 meshing with the rack bar, a pulley, a flexible member extended upward over the pulley and connected at opposite ends to the rack bar and block, a worm gear rotatable with the pinion and a worm journaled upon the 15 block and engaging the worm gear.

3. A hoisting mechanism including a vertically movable lifting bar, a vertically movable block, a pulley, a flexible connection extended upward over the pulley and connect- 20 ed at opposite ends to the block and lifting bar, and means upon the block for moving the lifting bar and block in opposite direc- tions.

4. A hoisting mechanism including a ver- 25 tical frame, a rack bar slidably mounted therein, a block slidably mounted in the frame, a pinion upon the block meshing with the rack bar, a pulley upon the upper portion of the frame, a flexible member extend- 30 ed over the pulley and connected at opposite ends to the block and rack bar, gears

rotatable with the pinion, oppositely disposed bearings upon the block, a worm shaft journaled in each set of bearings, a worm upon each worm shaft meshing with one of 35 said gears, means operatively connecting the worm shafts, and means for rotating one of the worm shafts.

5. A hoisting mechanism including an up- 40 right frame, a rack bar vertically slidable therein, a channel shaped block vertically slidable in the frame, the teeth of the rack bar extending into the channel thereof, a pinion within said channel block meshing with the rack bar, a pair of pulleys upon 45 opposite sides of the upper portion of the frame, a flexible member extended over each pulley and connected to the block and rack bar at opposite ends, a pair of worm wheels rotatable with the pinion and located upon 50 opposite sides of the frame, spaced ears upon opposite sides of the block, a pair of worm shafts journaled in said ears, a worm upon each shaft meshing with one of the worm 55 gears, pinions at the outer ends of the worm shafts, an idler upon the frame meshing with said pinions, and a flat sided shank upon one of the worm shafts for receiving a tool to rotate the same.

In testimony that I claim the above, I 60 have hereunto subscribed my name.

JOHN A. MORRISON.
